UNITED STATES PATENT OFFICE

ARTHUR H. BOETTCHER, OF EVANSTON, ILLINOIS, ASSIGNOR TO GULBRANSEN COMPANY, OF CHICAGO, ILLINOIS, A CORPORATION OF ILLINOIS

PLAYER PIANO

Application filed January 27, 1927. Serial No. 163,898.

This invention relates to player pianos, and more particularly to that type of player piano in which the action is exhausted by manually operated means as distinguished 5 from the so-called reproducer player piano in which the action exhausting means is power driven.

In player pianos of the type to which my invention is particularly adapted, the action is exhausted by a power unit operated by pedals. As the roll motor is connected to this unit and exhausted thereby, the volume of air handled is comparatively great, and of this volume 50% and sometimes more is 15 required for the operation of the roll motor. By providing suitable means for operating the music sheet winding and rewinding mechanism without the employment of a pneumatically actuated motor, the volume 20 of air required to be handled by the action exhausting means can be reduced by at least one-half. This gives a much more delicate and accurate control of the expression by the player and also renders it much easier 25 to operate the pedals. In view of the fact that the volume of air handled when the roll motor is eliminated is comparatively small, any change in the speed or rate of operation of the pedals will produce a relatively great change in the tension in the air 30 of the action system with a corresponding variation in expression. In view of this fact it will be obvious that, by reducing the volume of air to be handled, I greatly increase 35 the ease of operation of the exhausting unit, and I also give very delicate control of the expression. This latter feature is of particular importance as many persons prefer this type of player piano in view of the fact that the expression can be controlled by pedaling to suit the individual player. One great objection to the so-called reproducer player piano is that the expression control is automatic and the expression of a 45 selection cannot be controlled at the will of the operator, so that all individuality in playing selections is destroyed. This is the main reason why many people prefer the player piano of that type in which the action is exhausted by manually operated ex-

hausting means, and it will be obvious that any means which materially increases the accuracy and delicacy of control of the expression by the player is of great merit. This is particularly true where such means 55 also materially increases the ease of operation of the exhausting unit.

In its broader aspects my invention contemplates the elimination of the usual pneumatic motor employed for operating the spool and the roll chuck. I also provide means whereby the speed of rotation of the spool and the roll chuck can be readily varied within wide limits, such means being free of the effect of inertia and responding 65 instantaneously to any adjustment made for variation in speed. An additional feature of my invention is the provision of means for preventing operation of the spool until the proper air tension has been produced in 70 the action to ensure proper operation of the player pneumatic. Further objects and advantages will appear from the detailed description.

In the drawings:

Figure 1 is a front view of a player piano of known construction, with the front boards of the case removed, illustrating my invention as applied;

Figure 2 is a detail view, in elevation, of the two driving wheels and associated parts;

Figure 3 is a section taken substantially on line 3-3 of Figure 2;

Figure 4 is a diagrammatic view of the re-roll and tempo control levers and the 85 connections between the same and the shift lever and the wheel adjusting yoke, and associated parts;

Figure 5 is a diagram, in plan, of the parts illustrated in Figure 4;

Figure 6 is a diagram of the motor circuit;

Figure 7 is a plan view of the re-roll lever and associated parts illustrating a modified form;

Figure 8 is a section taken substantially on line 8-8 of Figure 7;

Figure 9 is a section taken substantially on line 9-9 of Figure 7;

Figure 10 is a fragmentary elevation of 100

the re-roll lever shaft and the motor reverse switch and associated parts;

Figure 11 is a fragmentary detail of one of the switch operating cams and its associated switch button;

5 Figure 12 is a fragmentary view of one end portion of the spool box and associated parts, showing the driving connections between the collar shaft and the spool and the roll chuck in the modified form illustrated 10 in Figures 7 to 11; and

Figure 13 is a diagram of the motor circuit in the form illustrated in Figures 7 to 11.

15 The player piano illustrated is of known construction and includes the pneumatic stack 1 with which are associated the player pneumatics (not shown), this stack being exhausted by means of a unit 2, the pump members or bellows 3 of which are operated 20 by pedals 4 in a known manner. The unit 2 includes a throat 5 connected by exhaust tube 6 to stack 1. This unit is disposed in the lower portion of the case beneath key bed 7 upon which are mounted the usual 25 sustaining and melody levers. A bracket shelf 8 is mounted above stack 1 and supports the spool box 9 in which are mounted spool 10, roll chucks 11 and 12, and tracker bar 13 in a known manner. The spool 10 and roll chuck 11 have driving connection 30 with a counter shaft 14, this connection being controlled by a shift lever 15 in a known manner for rotating the spool in winding direction, or rotating the roll chuck 11 in re-winding direction, as required. The piano so far described is of well known construction and its operation is well understood in this art and need not be set forth 35 more in detail.

40 A rectangular frame 16 is secured to bracket shelf 8 adjacent spool box 9. This frame rotatably supports an upper drive shaft 17 and a lower counter shaft 18 disposed coaxially with counter shaft 14 and, in fact, forming a continuation thereof. Preferably, shaft 18 is connected to shaft 45 14 by a suitable connecting device so that these two shafts can be disconnected if it becomes desirable or necessary, though the shafts 18 and 14 can be made in one piece. Shaft 17 is driven, by a worm drive 18', from a suitable electric motor 19 which should be of uniform speed, this motor being 50 mounted upon the bracket shelf 8.

55 The shafts 17 and 18 are provided with driving wheels mounted thereon and connected by a belt, these wheels being constructed for radial expansion and contraction. Each of the wheels includes a pair of 60 collars 19' and 20, collar 19' being freely slidable on the shaft and collar 20 being secured to the shaft. These collars are connected by supporting members or strips 21 65 of resilient material, these members being

preferably in the form of leaf springs which possess appreciable strength and rigidity. In the form illustrated there are four of these members and each is provided at its central portion with a belt receiving member 22 of concavo-convex cross-section, this member forming a segment of a pulley formed by contact with each other of the members 22 when the driving wheel on either shaft is reduced to its minimum diameter. A belt 23 passes about the members 22 of the respective driving wheel structures, establishing driving connection between the shafts 17 and 18.

70 An adjusting yoke 24 is slidably mounted on the shafts 17 and 18, the longer arm 25 of this yoke contacting with collar 19' slidable on shaft 17, the shorter arm 26 contacting with the collar 19' slidable on shaft 18. As will be noted more clearly from Figure 2, the collars 19' and 20 on shaft 17 are oppositely related to the corresponding collars on shaft 18, so that when the yoke is shifted in one direction one of the wheels will be expanded radially and the other 75 wheel contracted, and vice versa. This serves to vary the respective diameters of the wheels simultaneously and at the same rate and in opposite relation. As the respective diameters of the wheels are oppositely varied, slight movement of the yoke is sufficient to produce a very decided change in the speed of rotation of shaft 18 relative to shaft 15, giving very accurate control of the rate of rotation of spool 10 or of the roll 80 chuck 11, as desired. Though a somewhat similar result could be accomplished by other mechanism for giving this variable adjustment of the driving connections between the shafts, I prefer to employ the particular 85 type illustrated and described as this is instantaneously responsive to any changes in position of the yoke 24 and is free of rotating parts which, due to inertia, would in any way interfere with the immediate response of the driving connections to adjustments of the yoke to effect speed variations.

90 The yoke 24 is shifted into desired position by means of the tempo lever 27 (Figures 4 and 5) secured to the shaft 28 rockably mounted on the under face of key bed 7. This shaft is provided with an arm 29 connected by rod 30 to arm 31 of a vertical shaft 32 rockably mounted in suitable bearings at one end of the case. At its upper 95 end shaft 32 is provided with an arm 33 depending from the plate portion 24a of yoke 24. Shaft 32 is further provided with an arm 36 connected by a rod 37 to a slide rod 38 slidable in bearings 39 secured to 100 the under face of bracket shelf 8. A pointer 40 is secured on the slide rod 38 and extends through a slot 8a in shelf 8, this pointer moving in front of a tempo indicating dial (not shown). These connections be- 105

tween the tempo lever and the parts associated therewith are, broadly, old and well known in this art. The various arms of shaft 32 and shaft 28 are so proportioned that the movement of lever 27 will impart but relatively small movement to yoke 24 and will impart the proper movement to slide rod 38 to indicate the tempo. In Figure 2 the yoke is shown in central position, this being the position the yoke occupies when the tempo lever 27 is in the vertical position illustrated in Figure 4. With the yoke in this position the effective diameters of the driving wheels on shafts 17 and 18 are equal. 10 When the lever is moved to the left, as considered in Figure 4, the yoke 24 is moved similarly and acts to shift collar 19' on shaft 17 so as to expand the wheel on this shaft, collar 19' on shaft 18 being simultaneously shifted or slid along its shaft so as to correspondingly decrease the effective diameter of the driving wheel on this shaft. This results in increasing the speed of rotation of shaft 18 relative to the speed of rotation of shaft 17. The extent of increase thus produced will depend upon the extent to which the yoke 24 is shifted to the left. If the lever 27 be rocked in the other direction beyond central position, the speed of rotation 20 of the shaft 18 will be reduced relative to shaft 17. As the effective diameters of the driving wheels on the shafts are varied instantaneously with the shifting of the yoke 24, this gives a very quick and accurate control of the tempo. This arrangement also gives a very wide variation in the speed of shaft 18, which is frequently very desirable for the proper rendition of musical selections. 30 It is desirable that means be provided to assure that the belt 23 will at all times have proper frictional contact with the driving wheels for establishing uniform driving connection therebetween and avoiding slippage. 40 This result may be obtained by employing a belt possessing appreciable elasticity or by maintaining a nonelastic belt taut by a suitable belt tightener. I have illustrated the latter method diagrammatically in Fig. 3. 45 An idler pulley 25a is rotatably mounted at the upper end of an arm 25b pivoted at its lower end at 25c, on a support 25d for swinging movement. This arm is urged toward the belt by a light tension spring 25e. Idler pulley 25a presses against one run of the belt and acts in a known manner to take up any slack in the belt maintaining it at the proper degree of tautness to ensure maximum driving efficiency. 50 Shift lever 15 extends through a slot 8b through bracket shelf 8 and is provided at its lower end with an elongated head 41 which is slotted longitudinally for reception of a finger 42 formed at the inner end of a rod 43 which connects an arm 44 at the upper end of a vertical shaft 45 to the shift lever. This shaft 45 is mounted similarly to shaft 32 and is provided at its lower end with an arm 46 connected by a rod 47 to an arm 48 depending from a shaft 49 rockably mounted on the under face of key bed 7. The re-roll lever 50 is secured to the outer end of shaft 49 and is turned in a counter clockwise direction for moving the shift lever 15 into position for winding the music sheet onto the spool 10 off of roll 12. When this lever is rocked in the other direction shift lever 15 is thrown into position to re-wind the roll, as is well known. Rod 43 is connected to lever 15 by a tension spring 51. This spring permits movement of lever 50 beyond re-winding position. 60 A double acting switch 53 of known type is mounted upon one of the equalizer bellows 3a of the unit 2. This switch is connected in the circuit of the electric motor and includes push buttons 54 and 55 for closing and opening the motor circuit, respectively. An angle finger 56 is secured on the movable leaf of a pneumatic 57 which is mounted on equalizer bellows 3a and is in communication therewith. A button operating finger 58 is pivoted on the bellows throat at one end at 59 and is connected at its other end by a rod 60 to an arm 61 secured to shaft 49. Normally the shift lever 15 is in neutral position and the yoke 24 is in central position, the levers 50 and 27 being in the positions illustrated in Figure 4. In starting to play, assuming that the button 55 of switch 53 has been pressed and the circuit of the motor opened, the pedals 4 are first operated until the proper operating tension is produced in the action system. This serves to collapse the pneumatic 57 sufficiently to depress button 54, by means of bracket 56, closing the switch 53, and starting the motor. Lever 50 is then moved to the left, shifting lever 15 into winding position, and the speed of travel of the music sheet is controlled by lever 27. When the selection has been played lever 50 is moved in a clockwise direction into re-winding position, and the lever 27 is moved in a counter clockwise direction into its extreme position in this direction so as to rotate counter shaft 18 at high speed, rotating the roll chuck 11 and consequently roll 12, at high speed for re-winding the music sheet thereon. During this re-winding of the music sheet the pedals 4 are not operated so that the vacuum is not maintained in the action system. This permits the pneumatic 57 to be expanded by its associated spring, moving the finger 56 upwardly away from button 54, so as to permit of raising of this button. As soon as the music sheet has been completely re-wound lever 50 is moved into its extreme position in a clockwise direction causing the finger 70 75 80 85 90 95 100 105 110 115 120 125 130

58 to depress button 55, opening the switch, and stopping the motor.

In Figures 7 to 13, inclusive, I have illustrated a modified form of my invention in which the shift lever 15 and associated parts are omitted, the re-winding of the music sheet being accomplished by reversing the direction of the motor current and consequently the direction of drive of the motor. With this object in view I provide a reversing switch 62 of known type which is connected in the motor circuit. This switch 62 is provided with push buttons 63 and 64 for play and re-roll, respectively. A second switch 65 of known type is connected in series in the motor circuit and is provided with switch buttons 66 and 67 for closing and opening the motor circuit, respectively. Two pairs of arms 68 and 69 are secured to shaft 49 of the re-roll lever 50. Each arm is provided with a cam element 70 at its outer end, these cam elements being disposed for moving the switch buttons inwardly into operative position. Referring to Figures 8 and 9, it will be noted that the arms 68 are spaced apart somewhat further than the arms 69 so that the cams 70 of the first pair of arms lead the cam elements of the second pair of arms. In starting to play, the lever 50 is moved in a counter clockwise direction into full playing position. This movement of the lever serves to move button 63 of switch 62 inwardly so as to rotate the motor shaft in playing direction, after which button 66 of switch 65 is moved inwardly to close the motor circuit. When the selection has been played the lever 50 is moved in a clockwise direction into re-winding position at which time button 64 of switch 62 is moved inwardly reversing the direction of drive of the motor. When the music sheet has been completely re-wound lever 50 is turned into its extreme position in clockwise direction, moving the button 67 of switch 65 inwardly and opening the motor circuit.

When the reversing switch arrangement is used, the drive pinion and the re-roll sprocket are mounted upon the counter shaft 14 in such manner that the pinion is driven by the shaft only when the motor is operated in winding or playing direction, the sprocket rotating with the shaft only when the motor is driven in re-winding direction. Obviously there are numerous ways in which this can be accomplished, such as suitable ratchet and pawl devices, or clutch devices, and it is not thought necessary to illustrate or describe this feature in detail.

What I claim is:

66 1. In a player piano having an action and exhausting means therefor, a motor independent of the action exhausting means, and mechanical driving connections between said motor and the spool and the roll chuck of the piano.

2. In a player piano having an action and exhausting means therefor, a motor independent of the action exhausting means, and variable speed mechanical driving connections between said motor and the spool and the roll chuck. 70

3. In a player piano having an action and exhausting means therefor, a drive shaft driven independently of the action exhausting means, a counter shaft having driving connection with the spool and the roll chuck, and variable speed driving connections between the shafts. 75

4. In a player piano having an action and exhausting means therefor, an electric motor, a drive shaft driven from said motor, a counter shaft having driving connection with the spool and the roll chuck, and variable speed driving connections between the shafts. 80

5. In a player piano having an action and exhausting means therefor, a drive shaft driven independently of the action exhausting means, a counter shaft having driving connection with the spool and the roll chuck, and variable speed mechanical driving connections between the shafts. 85

6. In a player piano having an action and exhausting means therefor, an electric motor, a drive shaft driven from said motor, a counter shaft having driving connection with the spool and the roll chuck, and variable speed mechanical driving connections between the shafts. 90

7. In a player piano having pedal operated action exhausting means, a motor independent of the exhausting means, and mechanical driving connections between said motor and the spool and the roll chuck. 100

8. In a player piano having pedal operated action exhausting means, a motor independent of the exhausting means, and variable speed mechanical driving connections between said motor and the spool and the roll chuck. 105

9. In a player piano having pedal operated action exhausting means, a motor independent of the exhausting means, a counter shaft having driving connection with the spool and the roll chuck, a drive shaft driven from said motor, and variable speed driving connections between the shafts. 110

10. In a player piano having pedal operated action exhausting means, a motor independent of the exhausting means, a counter shaft having driving connection with the spool and the roll chuck, a drive shaft driven from said motor, and variable speed mechanical driving connections between the shafts. 115

11. In a player piano having pedal operated action exhausting means, an electric motor, variable speed driving connections between the motor and the spool and the roll chuck, and control means for adjusting said 120

driving connections and for closing and opening the motor circuit.

12. In a player piano having pedal operated action exhausting means, an electric motor, variable speed and reversible driving connections between the motor and the spool and the roll chuck, means for adjusting said driving connections, and a single control means for closing the motor circuit and reversing the drive, said control means acting to operatively connect the motor to the roll chuck when moved into one extreme position and to open the motor circuit upon continued movement beyond drive reversing position.

13. In a player piano, an electric motor, a drive shaft driven by said motor, a counter shaft, variable speed driving connections between said shafts, the forward drive pinion and the re-roll sprocket being mounted on the counter shaft, means for adjusting said driving connections, manual control means for moving the shift lever into spool driving position as the control means is moved into its extreme position in one direction, said control means moving the shift lever into roll chuck driving position and subsequently opening the motor circuit as the manual control means is moved into its extreme position in the other direction, and automatic control means supplemental to the manual control means for closing the motor circuit when the tension in the action exhausting means reaches a predetermined minimum, the motor circuit being normally open through said supplemental control means.

14. In a player piano, an electric motor, variable speed driving connections between the motor and the spool and the roll chuck, said connections including the shift lever, a control lever, operating connections between said control lever and the shift lever for moving the latter into either of its operative positions, said operating connections including yielding means permitting continued movement of the control lever after the shift lever has been moved thereby into full re-rolled position, a control switch in the motor circuit, means actuated by the control lever for opening said switch as said control lever is moved in one direction beyond re-roll position, and means actuated by the tension in the action exhaust unit for closing said control switch when the tension reaches a predetermined minimum.

15. In a player piano, an electric motor, driving connections between the motor and the spool and the roll chuck, the motor circuit being normally open, and means for closing the motor circuit when the air tension in the action exhaust system reaches a predetermined minimum.

16. In a player piano, an electric motor, driving connections between the motor and the spool and the roll chuck, the motor cir-

cuit being normally open, and means actuated by the air tension in the action exhaust system for closing the motor circuit when said tension reaches a predetermined minimum.

17. In a player piano, an electric motor, driving connections between the motor and the spool and the roll chuck, the motor circuit being normally open, and means in communication with the action exhaust system and actuated by the air tension therein for closing the motor circuit when said tension reaches a predetermined minimum.

18. In a player piano, an electric motor, driving connections between the motor and the spool and the roll chuck, a motor control lever, and means controlling the motor circuit and actuated by said lever when moved into one operative position for closing said circuit and driving the motor in music sheet unwinding direction, said controlling means also including means actuated by the lever when moved into its other operative position for reversing the direction of drive of the motor and subsequently opening the motor circuit.

19. In a player piano, an electric motor, driving connections between the motor and the spool and the roll chuck, a motor control lever, an operating switch in the motor circuit, a reversing switch in the motor circuit, means for closing the reversing switch in one direction and subsequently closing the operating switch as the control lever is moved into one operative position, and means for closing the reversing switch in the other direction and subsequently opening the operating switch by continued movement of the control lever into its other operative position.

20. In a player piano, a drive shaft, a counter shaft having driving connection with the spool and the roll chuck, driving wheels on the shafts, a belt establishing driving connection between the wheels, and means for varying the speed at which the counter shaft is driven through the wheels and belt while maintaining constant the relation between the belt and the wheels.

In witness whereof, I hereunto subscribe my name this 22nd day of January, 1927.

ARTHUR H. BOETTCHER.
